(57) **CLAIM**

The ornamental design for a bracelet, as shown and described.

DESCRIPTION

FIG. 1 is a perspective view of a bracelet showing my new design;

FIG. 2 is a perspective view thereof from the side opposite that shown in FIG. 1;

FIG. 3 is a further perspective view thereof, with the bracelet rotated from the position shown in FIG. 1;

FIG. 4 is an elevational view thereof;

FIG. 5 is an elevational view thereof from the side opposite that shown in FIG. 4;

FIG. 6 is an end view from one end thereof; and,

FIG. 7 is an end view from an opposite end thereof.
